MULTIMAGE CAMERA

Leslie R. Walstrom, Excelsior, Minn., assignor to
Multi Photo Camera Corporation

Filed Apr. 24, 1970, Ser. No. 22,638

Term of patent 14 years

Int. Cl. D16—01

U.S. Cl. D61—1

FIG. 1

FIG. 2

FIG. 3

FIG. 4

FIG. 5

FIG. 6

FIG. 7

FIG. 1 is a perspective view of a multiimage camera showing my new design;

FIG. 2 is a front elevational view of the camera;

FIG. 3 is a right-side elevational view of the camera;

FIG. 4 is a top plane view of the camera;

FIG. 5 is a bottom plane view of the camera;

FIG. 6 is a left-side elevational view of the camera; and

FIG. 7 is a rear elevational view of the camera.

I claim:

The ornamental design for a multiimage camera, as shown.
